(57) **CLAIM**

The ornamental design for a headlight daytime running light, as shown and described.

DESCRIPTION

FIG. 1 is a front left top perspective view of a headlight daytime running light according to the present invention.

FIG. 2 is a front left perspective view of the headlight daytime running light shown in FIG. 1.

FIG. 3 is a front view thereof.

FIG. 4 is a left side view thereof; and,

FIG. 5 is a top view thereof.

In the FIGS. 1 through 5, the daytime running is shown on a headlight, and the rest of the headlight is shown in de-emphasized and half-tone portions so as to illustrate environmental structure, which portions form no part of the claimed invention. More particularly, in these Figures the inventive headlight daytime running light is shown within the broken line, and the elements shown outside the broken line form no part of the claimed design, but are instead included to show environmental aspects thereof. For purpose of illustration the daylight running light is shown in a darker tone. The darker tone itself forms no part of the claimed design. The invention includes a second embodiment that contemplates a mirror image headlight daylight running light on the opposite side of the vehicle.

1 Claim, 5 Drawing Sheets
